UNITED STATES PATENT OFFICE

CHARLES C. SPREEN, OF DETROIT, MICHIGAN, ASSIGNOR TO KELVINATOR CORPORATION, OF DETROIT, MICHIGAN, A CORPORATION OF MICHIGAN

MECHANICAL REFRIGERATION

Application filed March 8, 1926. Serial No. 93,005.

My invention relates to mechanical refrigeration, and is particularly applicable to mechanical refrigeration designed for cooling refrigerator cabinets of the household or store type, and the principal object of my invention is to provide a new and improved brine tank particularly suitable for such household and store installations. In the drawings accompanying this specification and forming a part of this application, I have shown, for purpose of illustration, one form which my invention may assume. In these drawings:

Figure 1 is a general front elevation of a refrigerator cabinet showing a brine tank embodying my invention,

Figure 2 is a section through this brine tank parallel to the view of Figure 1 and just within the front wall, while

Figure 3 is a horizontal section taken on the line 3—3 of Figure 2.

The brine tank 11 herein shown is positioned within the cooling compartment 12 of a refrigerator cabinet 13 having in addition a supplemental refrigerated compartment 25 disposed below the cooling compartment 12 and a main refrigerated compartment disposed beside the cooling compartment 12 and the supplemental refrigerated compartment, the cooling compartment 12 and the supplemental refrigerated compartment and the main refrigerated compartment being accessible, respectively, through doors 14 and 15 and 16.

The brine tank 11 herein shown comprises side walls 17, a front wall 18, a rear wall 19, a top 20, and a bottom 21, and is provided with two vertically aligned tubes 22 extending between the front wall 18 and the rear wall 19 and each forming, within the confined 40 of the brine tank 11, a recess 23 suitable for the reception of means for the production of artificial ice by the cold of the brine tank 11.

Positioned within this brine tank 11 for the purpose of cooling the brine within the 45 tank is an expansion coil 24 comprising three coils 25 and 26 and 27 disposed respectively in the three vertically aligned spaces 28 and 29 and 30 defined by the two vertically aligned tubes 22, and comprising also a duct 31 connecting the inlet end of the lower coil 27 to

the expansion valve 32, a duct 33 connecting the outlet end of the coil 27 to the inlet end of the center coil 26, a duct 34 connecting the outlet end of the coil 26 to the inlet end of the upper coil 25, and a duct 35 connecting the outlet end of the coil 25 to the end turns 36 of the thermostat 37, the coils 25 and 26 and 27 being intentionally positioned between the tubes 22 in order to facilitate removal of each coil from the brine tank for repair and to 55 overcome the difficulties attendant upon such removal when the coil surrounds a tube, and the connecting ducts 31 and 33 and 34 being disposed all on the same side of the tubes 22 to facilitate withdrawal of the coil 24 as a 60 unit and obviate the difficulties which would attend removal of the unit 24 were the connecting ducts disposed partly on one side of the tubes 22 and partly on the other side of the tubes 22.

From the above description it will be obvious to those skilled in the art that I have provided new and improved brine tank means particularly suitable for mechanical refrigeration of the household and store type. 75 At the same time, it will also be apparent to those skilled in the art that the particular embodiment of my invention herein shown may be variously changed and modified without departing from the spirit of my invention or sacrificing the advantages thereof, and it will therefore be understood that the disclosure herein is illustrative only and that my invention is not limited thereto.

I claim:

1. In a mechanical refrigerating system, a brine tank provided with at least two vertically aligned recesses extending into said tank from a lateral face thereof, each formed to receive a receptacle for the production of 90 artificial ice, and dividing said brine tank vertically into at least three aligned spaces; and a refrigerant expansion unit disposed within said tank and comprising at least two coils each disposed in one of said spaces. 95

2. In a mechanical refrigerating system, a brine tank provided with at least two vertically aligned recesses extending into said tank from a lateral face thereof, each formed to receive a receptacle for the production of 100

- artificial ice, and dividing said brine tank vertically into at least three alined spaces; and a refrigerant expansion unit disposed within said tank and comprising at least three coils each disposed in one of said spaces.
3. In a mechanical refrigerating system, a brine tank provided with at least two vertically alined recesses extending through said tank between opposite lateral faces thereof, each formed to receive a receptacle for the production of artificial ice, and dividing said brine tank vertically into at least three alined spaces; and a refrigerant expansion unit disposed within said tank and comprising at least two coils each disposed in one of said spaces.
4. In a mechanical refrigerating system, a brine tank provided with at least two vertically alined recesses extending through said tank between opposite lateral faces thereof, each formed to receive a receptacle for the production of artificial ice, and dividing said brine tank into at least three alined spaces; and a refrigerant expansion unit disposed within said tank and comprising at least three coils each disposed in one of said spaces.
5. In a mechanical refrigerating system, a brine tank provided with a recess extending into said tank from a lateral face thereof, said recess being formed to receive a receptacle for the production of artificial ice, and to divide said brine tank vertically into two spaces; and a refrigerant expansion unit disposed within said tank and comprising coils disposed in one of said spaces and extending substantially the entire length thereof, and connections connecting said coils and all lying on the same side of said recesses.
6. In a mechanical refrigerating system, a brine tank provided with a recess extending through said tank between opposite lateral faces thereof, said recess being formed to receive a receptacle for the production of artificial ice, and to divide said brine tank vertically into two spaces; and a refrigerant expansion unit disposed within said tank and comprising two coils each disposed in one of said spaces, and connections connecting said coils and all lying on the same side of said recesses.
7. In a mechanical refrigerating system, a brine tank provided with at least two vertically alined recesses extending into said tank from a lateral face thereof, each formed to receive a receptacle for the production of artificial ice, and dividing said brine tank vertically into at least three alined spaces; and a refrigerant expansion unit disposed within said tank and comprising at least two coils each disposed in one of said spaces, and connections connecting said coils and all lying on the same side of said recesses.
8. In a mechanical refrigerating system, a brine tank provided with at least two verti-
- cally alined recesses extending into said tank from a lateral face thereof, each formed to receive a receptacle for the production of artificial ice, and dividing said brine tank vertically into at least three alined spaces; and a refrigerant expansion unit disposed within said tank and comprising at least three coils each disposed in one of said spaces, and connections connecting said coils and all lying on the same side of said recesses.
9. In a mechanical refrigerating system, a brine tank provided with at least two vertically alined recesses extending through said tank between opposite lateral faces thereof, each formed to receive a receptacle for the production of artificial ice, and dividing said brine tank vertically into at least three alined spaces; and a refrigerant expansion unit disposed within said tank and comprising at least two coils each disposed in one of said spaces, and connections connecting said coils and all lying on the same side of said recesses.
10. In a mechanical refrigerating system, a brine tank provided with at least two vertically alined recesses extending through said tank between opposite lateral faces thereof, each formed to receive a receptacle for the production of artificial ice, and dividing said brine tank into at least three alined spaces; and a refrigerant expansion unit disposed within said tank and comprising at least three coils each disposed in one of said spaces, and connections connecting said coils and all lying on the same side of said recesses.
11. In a mechanical refrigerating system, a brine tank provided with a recess extending into said tank from a lateral face thereof, said recess being formed to receive a receptacle for the production of artificial ice, and to divide said brine tank vertically into two spaces; and a refrigerant expansion unit disposed in each of said spaces, said coils extending substantially the entire length of said spaces and removable from said tank in a direction parallel to said lateral face.
12. In a mechanical refrigerating system, a brine tank provided with a recess extending through said tank between opposite lateral faces thereof, said recess being formed to receive a receptacle for the production of artificial ice, and to divide said brine tank vertically into two spaces; and a refrigerant expansion unit disposed within said tank and comprising two coils each extending substantially the entire length of and disposed in one of said spaces.
- In testimony whereof I hereunto affix my signature.
- CHARLES C. SPREEN.
